Primary Examiner — Ian Simmons*Assistant Examiner* — Carissa C Fitts(74) *Attorney, Agent, or Firm* — Barnes & Thornburg LLP(57) **CLAIM**

We claim the ornamental design for a broach, as shown and described.

DESCRIPTION

FIG. 1 is a top-front perspective view of a design of the broach;

FIG. 2 is a front elevation view of the broach of FIG. 1;

FIG. 3 is a rear elevation view of the broach of FIG. 1;

FIG. 4 is a top plan view of the broach of FIG. 1;

FIG. 5 is a bottom plan view of the broach of FIG. 1;

FIG. 6 is a first side elevation view of the broach of FIG. 1; and,

FIG. 7 is a second side elevation view the broach of FIG. 1. The broken lines represent unclaimed portions of the article and form no part of the claimed design. The dash-dot-dot-dash broken line in FIG. 1 indicates a boundary of claimed subject matter.

1 Claim, 4 Drawing Sheets(56)
